TACK BUTTON

Franklin R. White, Waterbury, Conn., assignor to
 The Patent Button Company, Waterbury,
 Conn., a corporation of Connecticut

Application January 19, 1935, Serial No. 2,571

3 Claims. (Cl. 24—95)

My invention relates to new and useful improvements in tack buttons, and has for an object to provide a button that is relatively cheap to manufacture and extremely durable in service.

- 5 As is well known, tack buttons generally consist of the button head proper, in which head there is means provided for deflecting and deforming a tack, and a rivet or tack, which latter is to be driven into the button head.
- 10 Tack buttons are applied by placing a number of the button heads in the one hopper of a "button attaching machine" and supplying another hopper with the tacks, so that as the machine is operated, the button heads will be fed down to the table and onto the article to which the button head is to be attached, while, in turn, the tacks are driven up through the material into the button head where they are curled or deformed during the attaching operation to thus form a permanent fastening of the button to the cloth.

15 The present button in its broadest aspects resembles the type of button shown in the patent granted to me, Walter T. Abel, and Leonard R. Carley, Number 1,744,350, on January 21, 1930, for Tack buttons, and also is similar in its general aspects to the button shown in a companion application filed by me on November 2, 1934, bearing Serial Number 751,209, for Tack buttons.

20 In the above-mentioned application, I provided a disk with a central opening, which registers with an opening in the hub of the button, so that the side walls of the disk about the opening may act as a guide for the tack during its entrance into the button head. I have found, however, 25 that at times it may be desirable to have guiding walls for the tack that will extend still further into the button head to more firmly guide the tack during its entrance.

25 Another object, therefore, of the present invention is to provide an additional reinforcement in the lower extremity of the hub of the button, the reinforcement being so pierced that the broken walls about the piercing will extend a material way up into the button head to thus more firmly guide the tack into position.

30 Still another object of the invention is to provide an anvil to cooperate with the tack, the said anvil provided with a semicircular pocket in which the tack will be deformed and which pocket is of greater area or diameter than the opening in the bottom of the hub of the button.

35 Still another object of the invention is to so construct this anvil that it will entirely fill the shell or button back. Thus, when pressure is applied to the button head in the attaching ma-

chine, there will be no possibility of the peripheral rim sagging or the center of the button rising, which latter might disfigure the ornamentation of the button cap.

40 With these and other objects in view, the invention consists in certain new and novel features and combination of parts, as will be hereinafter more fully explained and pointed out in the claims.

45 Referring now to the drawing showing a preferred embodiment of my invention,

Fig. 1 is an enlarged sectional view of my improved button showing the reinforcing plate within the slightly enlarged end of the hub and also showing how the metal centrally of the reinforcing plate, as well as the hub, has been forced inwardly and upwardly to form what might be termed a tubular guide for the tack;

50 Fig. 2 is a side elevation of the button after being attached to the cloth, fragmentarily showing a portion of the attaching plunger and table and the manner in which the plunger is cut out to preserve the ornamentation of the cap during the attaching operation;

55 Fig. 3 is a bottom plan view of the button showing how the same is to be pierced with a punch or draw pin having preferably a triangular point;

60 Fig. 4 is a sectional view of the die or anvil of the button head;

65 Fig. 5 is a similar view of the button shell with the reinforcing plate therein, the shell and plate having been pierced to provide relatively long guide walls for the proper guidance of the tack; and

70 Fig. 6 is a perspective of the reinforcing plate.

75 Referring now more particularly to the several views, and for the moment to Figs. 1 and 5, there is shown the button back or shell having what I term the body portion 1, the upwardly and outwardly extending flange 2, and the slightly tapered integral hub 3. This shell or button back is formed of relatively thin metal and as far as described is conventional in construction.

80 However, there will be seen fitted into the lower end of the hub the reinforcing plate 4 which, of course, will be inserted under high pressure, and as the diameter of the plate is slightly greater than the lower inside diameter of the hub 3, the hub will flare slightly outwardly, as at 5. This is also shown in the companion application above-mentioned.

85 Rather than having a circular opening in the reinforcing plate, as is shown in the companion case, I prick-punch the bottom wall of the hub 55

of the button shell to form the opening 6, and preferably with a punch (not shown) having a triangular point, the body of the punch being round, so that as this punch is driven up through 5 the shell and plate it will drive the fractured metal 7 of the shell for a material distance up into the shell. In driving up this fractured shell, it will also drive up the metal 8 of the reinforcing plate 4, and this metal 8, it will be noticed, 10 in reality forms a rim that rigidly reinforces the metal 7 of the shell, to thus provide what I term a tube for the guidance of the tack prong or rivet. It will be understood that the bottom and side walls of the hub are also strengthened by 15 this reinforcing plate 4.

Referring for the moment now to Figs. 1 and 4, there is shown the anvil or slug 9, consisting of what might be termed the body 10 and the integral hub 11, the hub, in turn, having the 20 semi-circular cavity or pocket 12 formed therein, the diameter of which, it will be noticed, is slightly larger than the diameter of the tube formed in the button shell, so that there is no possibility of the tack not being properly curled during the 25 attaching operation.

In Fig. 1, it may be seen that the diameter of the body 10 is such that it will entirely fill the button shell directly beneath the cap 13, and it will also be noticed that the sides of the body 10 30 are tapered, as at 14, to conform to the tapering walls 2 of the button shell. The cap may be ornamented, as at 15, with any desired insignia.

Further, it will be noticed that the hub portion 11 of the slug or anvil is of a size to snugly 35 fit within the hub of the button shell. Thus, it will be seen that the shell of the button is practically filled with the slug or anvil, with the exception of the slight space between the lower ends of the hub and the reinforcing plate 4. In this 40 way, the shell is reinforced substantially throughout its entire structure. The cap will be crimped, as at 16, about the flaring walls 2 of the shell, as is the usual practice.

As heretofore mentioned, when the button is 45 to be attached, a tack 17 below the material 18 is supported by the anvil 19, so that when the plunger 20 descends, the prong of the tack will be driven upwardly through the cloth and through the opening 6 and will be properly guided by the 50 metal 7 which is of tube-like form. Now, as the plunger continues its descent and drives the button head (with the anvil having its hemispherical pocket) onto the tack, the tack will be deformed, as at 21, (Fig. 2), to tightly grip the 55 button head to the material.

It will be seen that the metal 7 which forms the tube-like portion acts as a substantial guide for the tack and holds the same upright while the point is being curled or deformed. Also by 60 providing this tube, the prong of the tack being held in an upright position, of course, prevents the head 22 of the tack from shifting or, as might be termed, "skidding".

It will also be noticed that by providing an 65 anvil or slug, which entirely fills the button shell or back, it will be possible to have the plunger 20 cut-out, as at 23, so that the outer rim 24 of the plunger will contact with the peripheral rim of the cap rather than with the entire cap, thus preventing 70 any insignia on the cap from being mutilated or disfigured. At the same time, even

though the power is applied peripherally to the button head, the slug entirely filling up the button cap will prevent the peripheral rim of the button head from being bent downwardly with respect to the center. 5

I have found in the actual building of buttons of this type with a reinforcing plate therein, by simultaneously piercing both the shell and the plate with a triangular end punch, the fractured metal is driven for a distance up into the cap, 10 substantially forming a tube, which tube, in turn, is reinforced by the fractured metal of the reinforcing plate, so that when the buttons are attached in the button attaching machine the tack will always correctly enter the opening of 15 the hub and will be prevented from skidding or tilting to thus be properly curled and deformed during the attaching operation.

It will be seen that in this instance the fractured metal of the shell that is driven upwardly 20 into the button head is well reinforced at or near its upper extremity by the fractured metal of the reinforcing plate, which is not true of the companion application referred to.

Many slight changes are possible in the construction hereinbefore set forth without departing 25 from the principle and spirit of the invention.

Having thus described my invention, what I claim as new and desire to secure by Letters Patent is:— 30

1. A tack button comprising a shell, said shell formed of relatively soft metal and having an upwardly extending peripheral rim, an integral hub having a slightly enlarged lower extremity, a reinforcing disk of relatively hard metal clamped 35 within said enlarged extremity, an anvil having a pocket and the anvil fitted within the hub, a cap over said shell, the bottom wall of the hub and the reinforcing plate being perforate and the displaced metal caused by the perforation forming a tube-like entrance for a tack, and the walls of the tube-like entrance adapted to hold the tack in an upright position during an attaching operation. 40

2. A tack button comprising a shell, said shell 45 formed of relatively soft metal and having an upwardly extending peripheral rim, an integral hub, a hard metal reinforcing plate held within the hub and at the lower extremity of said hub, the lower wall of said hub and the said disk being 50 roughly perforated, the fractured metal of the perforation of the bottom wall of the hub and of the reinforcing member forming substantially a reinforced tubular opening for the reception and guidance of a tack. 55

3. A tack button comprising a shell formed of relatively thin metal and having an upwardly and outwardly extending peripheral rim, an integral hub, a hard metal reinforcing plate held within the hub and at the lower extremity thereof, an 60 anvil having a central cavity fitted within the shell and substantially completely filling the same, a cap crimped over said shell and in contact with said anvil, the bottom wall of the shell and the reinforcing member being pierced, and 65 the fractured metal caused by the puncture of both the thin and hard metal extending upwardly into the hub to form a tube-like guide for the tack to the cavity walls of the anvil. 70
